RAYMOND L. MORRIS, OF HONOLULU, TERRITORY OF HAWAII, ASSIGNOR TO LEWERS & COOKE, LTD., OF HONOLULU, HAWAII, A CORPORATION OF HAWAII.

BUILDING BLOCK.

Application filed September 8, 1926. Serial No. 134,263.

The present invention is concerned primarily with the provision of a building block for use in foundation work which is so designed that it will effectively prevent 5 ground-nesting termites or similar insect pests from gaining access to the woodwork which is supported above the foundation.

The termites in certain localities, particularly in Hawaii, cause serious damage to 10 building structures of all kinds, and are apparently capable of going through any sort of building material, except metal and solid concrete. The present invention aims to provide a foundation block equipped with a 15 metal guard which will prevent the passage of the termites from the ground to the super-structure.

An object of the invention is to provide a block of this character, preferably of concrete, which may be handled in the ordinary 20 manner, and which is so constructed that the metal guard plate which is associated with it, does not interfere with the ordinary stacking of the blocks and is guarded 25 against the collection of débris thereon by being set inwardly from the outer face of the block.

Other objects of the invention are to provide a block of this general character of 30 simple, practical construction, which will be rugged, durable and efficient in use, and which is well suited to the requirements of economical manufacture.

With the above noted and other objects in 35 view, the invention consists in certain novel features of construction and combinations and arrangements of parts, as will be more fully hereinafter set forth and pointed out in the claims. The invention may be more 40 fully understood from the following description in connection with the accompanying drawings, wherein—

Fig. 1 is a perspective view showing a 45 concrete block embodying the present invention.

Fig. 2 is an enlarged vertical sectional view on the line 2—2 of Fig. 1.

Fig. 3 is an enlarged sectional plan view on approximately the line 3—3 of Fig. 2.

Fig. 4 is a view similar to Fig. 1, but 50 illustrating a slightly modified form of block.

Fig. 5 is a vertical sectional view on the line 5—5 of Fig. 4.

Fig. 6 is a sectional detail illustrating the 55

manner of supporting a building upon the blocks.

As will be more fully explained in the latter portion of the specification, the blocks may assume many forms and many shapes. 60 For the sake of illustration, I have shown a block of general rectangular or cubical formation, but it is to be understood that the drawings are not to be interpreted in a limiting sense. 65

The block includes approximately parallel upper and lower rectangular faces 10 and 11 and approximately rectangular side faces 12. It may be formed of any suitable material which is free from voids. Cast into the 70 block is a guard plate 13 preferably of the same general shape as the top and bottom surfaces of the block, but of slightly smaller dimensions. Plate 13 is preferably provided with a central opening 14 therein, so that the 75 concrete or other material of the block may form a bond throughout and insure the retention of the plate in proper position. Side faces 12 of the block are preferably formed with relatively wide deep grooves 15 which 80 expose the lateral edges of the plate 13. The plate edges are spaced inwardly a sufficient distance so that they are protected by the top and bottom of the block against falling débris, against accidental injury, and to permit the ordinary stacking and handling of 85 the blocks.

Preferably the edges of the plate are sharpened as indicated at 16 in Figs. 1, 2 and 3, although they may if desired, be 90 downwardly flanged as at 17 in Figs. 5 and 6. In the latter instance the ends of the flanges 17 are welded together or the flanged plate is formed by a single stamping operation, so that the flanges will be continuous. 95

Obviously the block instead of having rectangular upper and lower faces, might be of any regular polygonal shape in horizontal cross section. The grooves 15 instead of being V-shaped might assume many other forms, and while I have shown the plate edges treated in two ways to prevent the passage of termites, any other method of shaping or treating the edges of the plate to accomplish this result would be within 105 the spirit of the present invention.

The manner of using the blocks is to mount them directly upon a stone footing, such as 20 in Fig. 6, and support the wooden foundation posts 21 upon the blocks, the 110

superstructure of the building being formed in any desired manner.

I may briefly explain the manner in which the guard plate 13 serves to prevent the termites from reaching the wooden portion of the building as follows. The ground-nesting termites will not work in the light, and in cases where they have to come into the open air, they build runways or tunnels 10 of bits of wood, dirt, etc., through which they find access to other protected spots. It has been proved that the termite will not build his runway over the sharp edge of a piece of metal on account of the difficulty 15 which he encounters in balancing his heavy body and working on the runway at the same time. The metal guard is thus effective, and if the block is of solid concrete without voids, there is no danger of the termite working his way through the block. In an attempt to reach the wooden building 20 which is supported above the blocks, the termite will have to come into the light and build a runway over the block until the metal guard plate is reached, at which point it will be effectively stopped.

Débris from the building operation is extremely unlikely to collect on the projecting guard plate, inasmuch as this plate is protected by the upper portion of the block and is set inwardly from the extreme lateral edges of the block. There is also no danger of damaging the plate by accidentally dropping material upon it, and there is no inconvenience encountered in the ordinary 35 shipment, handling or stacking of the blocks.

Obviously the sizes of the blocks might be considerably varied, it being sufficient for all practical purposes if they are high enough 40 to support the wooden portion of the building about six inches above the ground.

Various changes and alterations might be made in the general form and arrangement of parts described without departing from 45 the invention. Hence I do not wish to limit myself to the details set forth, but shall consider myself at liberty to make such changes and alterations as fairly fall within the spirit and scope of the appended claims.

50 I claim:

1. A building block including top and bottom faces and side faces and a plate projecting laterally from the side faces of the block, the edges of said plate being shaped to prevent the passage of ground-nesting termites or similar insect pests from the bottom to the top thereof.

2. A building block including top and bot-

tom faces and side faces and a plate projecting laterally from the side faces of the block, the edges of said plate being shaped to prevent the passage of ground-nesting termites or similar insect pests from the bottom to the top thereof, said plate edges being 65 sharpened.

3. A building block including top and bottom faces and side faces and a plate projecting laterally from the side faces of the block, the edges of said plate being shaped to prevent the passage of ground-nesting termites or similar insect pests from the bottom to the top thereof, said plate being turned downwardly to form a continuous depending flange.

4. A building block including top and bottom faces and side faces and a plate projecting laterally from the side faces of the block, the edges of said plate being shaped to prevent the passage of ground-nesting termites or similar insect pests from the bottom to 70 the top thereof, the sides of said block being grooved and said plate edges lying within said groove.

5. A building block including top and bottom faces and side faces and a plate projecting laterally from the side faces of the block, the edges of said plate being shaped to prevent the passage of ground-nesting termites or similar insect pests from the bottom to the top thereof, the sides of said block having V-shaped grooves therein and the plate projecting laterally from the bottom of said 80 grooves and terminating short of the lateral edges of the top and bottom of the block.

6. A molded concrete block having approximately parallel top and bottom faces, a plate molded in the block and lying between and in substantial parallelism with said faces, the edges of the plate projecting laterally from the body of the block and being 90 shaped to prevent the passage of termites from the bottom to the top of the block.

7. A molded concrete block having approximately parallel top and bottom faces, a plate molded in the block and lying between and in substantial parallelism with said faces, the edges of the plate projecting laterally from the body of the block and being shaped to prevent the passage of termites from the bottom to the top of the block, 100 said block having recesses in its side faces exposing the outer edges of the plate and said plate being of similar shape and smaller size than the top and bottom faces of the block.

RAYMOND L. MORRIS.
